WIRE BASKET FOR BOTTLES

Leonard H. Schwarz, Hartford, Conn.

Application November 25, 1949, Serial No. 129,212

10 Claims. (Cl. 224—48)

1

This invention relates to carrying baskets for a small number of bottles and particularly to a wire basket that will permit the bottles while disposed in the basket to be placed in a box or tray divided by vertical partitions or walls to form compartments for individual bottles.

An object of importance of the invention is that the basket may be formed of a small number of metal parts that can be readily made by conventional sheet stamping and forming and wire bending equipment.

Another feature that is important is that each bottle is retained in position by a single bent wire member, the wire members for retaining each bottle being identical and each bent wire being attached to a central sheet metal member held between the opposite side panels thereof.

A feature that enables the above objects to be accomplished is that the ends of the bent wire members are bent back on themselves and are held between crimped portions of the side panels of the sheet metal member held rigidly together by closely positioned rivets.

And another feature of the invention that is important is that reinforcing members formed of small sheet metal pieces may be crimped about upper intermediate portions of the bent wire members to more rigidly retain these members in their correct bottle retaining positions.

With the above and other objects in view the invention may include the features of construction and operation set forth in the following specification and illustrated in the accompanying drawings.

In the accompanying drawings annexed hereto and forming a part of this specification, I have shown the invention embodied in a wire basket for carrying six individual small size beverage bottles but it will be understood that the invention can be otherwise embodied and that the drawings are not to be construed as defining or limiting the scope of the invention, the claims appended to this specification being relied upon for that purpose.

In the drawings:

Fig. 1 is a side elevation of a wire basket made in accordance with the present invention with bottles positioned therein and with the basket and bottles fitting within a portion of a box or tray divided into compartments for individual bottles;

Fig. 2 is a plan view of the carrier, bottles and tray or box shown in Fig. 1;

Fig. 3 is an end elevation of the carrier and bottles shown in Figs. 1 and 2;

Fig. 4 is a fragmentary plan view on an enlarged scale, partially broken away to more clearly show the details of construction of the bent wire members and the sheet metal member;

Fig. 5 is a vertical sectional view taken on the plane of line 5—5 in Fig. 1;

Fig. 6 is a separated view of one of the bottle embracing and retaining wires, and

2

Fig. 7 is a separated view of a detail the view being taken from the inside of the basket.

In the above mentioned drawings, there has been shown but one embodiment of the invention which is now deemed preferable, but it is to be understood that changes and modifications may be made within the scope of the appended claims without departing from the spirit of the invention.

Briefly, and in its preferred aspect, the invention may include the following principal parts: First, a central panel member preferably of sheet metal folded centrally upon itself; second, a handle attached thereto, and third, similar individual bent wire members attached to the central sheet metal panel at their upper ends and adapted for retaining and supporting individual bottles slightly spaced apart.

Referring more in detail to the figures of the drawing it will be seen that the basket includes a central panel member 10 which preferably and as shown is of thin sheet metal doubled along its lower horizontal edge to form two parallel walls 12 slightly spaced apart. As shown also in the figures the side and top edges 14 of these panels 12 are crimped together to permanently hold the panels in closely adjacent parallel positions.

Passing through spaced openings provided in the upper edge of the panel member are the opposite end portions of a metal handle or loop 16. The extreme ends of the handle 16 are bent inwardly as shown in Fig. 1 at 18 to prevent complete removal of the handle from the panel member 10 but permitting upward and downward movements of the handle for compactness and to permit stacking of the grouped basket held bottles as shown in Fig. 3.

Entering pairs of spaced holes in the side surfaces 12 of the panel member 10 are the opposite ends 20 of bent wire members 22 so shaped in their central portions that each supports a bottle 24 in position by engaging against the bottom of the bottle and by contacting its sides. The shape of the individual wire members 22 is clearly shown in Fig. 6, and each wire member is identical with the others. The lower central part 26 forms a support or platform on which the bottom surface of a bottle 24 rests. This supporting section 26 of the wire 22 also permits a basket with its bottles to be mounted in position upon a similar basket with bottles whether provided with caps or not. On either side of the wire member is a long vertical portion and adjacent the top these vertical members are bent into curved form 28 to enclose the bottle 24 near its upper full diameter portion. The opposite ends 20 of the wire members 22 are passed through openings formed in the side panels 12 of the sheet metal member 10 and are bent downward. To retain these end portions 20 rigidly in position between the panels 12 of the sheet metal member 10 the panels 12 are crimped together as shown at 30

in Figs. 1, 4 and 5 and these crimped portions 30 are secured together by rivets 32 as shown in the above-mentioned figures. As will be seen particularly in Fig. 4 individual pockets are formed between the panels 12 at their crimped portions 30 within which one of the wire ends 20 extends. These pockets, it will be seen in Fig. 4, are disposed along the side of the panel member 12 opposite the openings through which they extend.

To aid in maintaining the bent wire members 22 in fixed position adjacent wires of these members may be attached to a reinforcing member 34. As shown in Figs. 1, 2 and 7 the reinforcing members 34 may be formed of thin sheet metal extended portions of which may be crimped about the upper portions of the wire retainers 22 for adjacent bottles 24.

The construction described above provides a basket retaining and supporting six bottles in a group each bottle 24 being slightly spaced from the others so that the basket with its bottles may be placed in a tray 36 provided with partitions to form individual compartments for the bottles. The bent wires 22 of the basket fit closely enough to the bottles 24 so that they will enter the spaces of the individual compartments of the tray and permit the bottom portions 26 of the bent wires to rest with the bottles on the bottom of the box or tray.

In its lowermost position the handle 16 rests below the upper ends of the bottles so that in this position it does not interfere with the stacked up baskets with their bottles one above the other.

I claim as my invention:

1. A carrier for bottles comprising in combination, a vertical central panel member, a handle mounted therein, and individual wire members bent into loop form and attached at their upper ends only to said panel member, each of said wire members being bent to engage the lower surface of a bottle and adapted to support and retain said bottle in position against and below said panel member.

2. A carrier for bottles comprising in combination, a vertical central panel member comprising adjacent walls having an open space therebetween, a handle on said panel member, and individual wire members bent downward into loop form and having their upper ends extending within the space between the walls of said panel member, said wire members each having portions bent to extend below a bottle and adapted to support and retain said bottle in position against and below said panel member.

3. A carrier for bottles comprising in combination, a vertical central panel member, a handle thereon, and a plurality of individual identically looped wire members depending from said panel member to extend below the bottom surface of a bottle and attached at their upper ends to said panel member, whereby each of said wire members is adapted to support and retain a bottle in position against and below said panel member.

4. A carrier for bottles comprising in combination, a vertical central panel member, a handle thereon, and a plurality of spaced apart looped wire members individually attached to and depending from said panel member, said wire members each having a portion extending below the bottom of a bottle and adapted to support and retain a bottle against said carrier with said bottles in slightly spaced apart relation to each other.

5. A carrier for bottles comprising in combina-

tion, a vertical central panel member, a handle thereon, a plurality of bent wire members individually secured at their upper ends thereto and depending therefrom, said members each being adapted individually to support and retain a bottle, and a reinforcing member attached to the upper portions of adjacent wires to retain said wire members in position.

6. A carrier for bottles comprising in combination, a vertical central panel member, a handle thereon, a plurality of bent wire bottle retaining members individually secured at their upper ends to said panel member and depending therefrom, the central lower end of said wires fitting within the bottom recess of a bottle and intermediate portions of said wires surrounding said bottles, whereby said bottles are supported and retained by said carrier.

7. A carrier for bottles comprising in combination, a vertical central panel member, a handle thereon; a plurality of bent wire members individually secured at their upper ends to said panel member and depending therefrom, said members each adapted to enclose a bottle, the central lower portion of said members extending centrally below the bottle and within the central recess therein.

8. A carrier for bottles comprising in combination, a vertical central panel member, a handle thereon, a plurality of bent wire members individually secured at their upper ends to said panel member and depending therefrom, said members each adapted to enclose a bottle, the central lower portion of said members extending centrally below the bottle within the central recess therein and adapted to rest on the bottle caps of bottles in another similar carrier.

9. A metal carrier for a group of spaced apart bottles comprising in combination, a vertical central plate member, a handle mounted therein, and wire members bent into loop form and attached at their upper ends to said plate member, said wire members at their lower portions being bent inwardly to engage the central bottom recess of the bottles and support said bottles in regular spaced apart relation.

10. A metal carrier for a group of spaced apart bottles having centrally recessed bottom surfaces comprising in combination, a vertical central plate member, a handle mounted therein, and wire members depending from said central plate member bent into loop form and having their opposite ends attached to said plate member, said wire members serving to individually engage the central bottom recess of a bottle and collectively support said bottles in regular spaced apart relation.
